COMPOUND CARDBOARD BOX BODY

George H. Snyder, Glenside, and Allen G. Snyder,
Chestnut Hill, Pa.

Application March 28, 1936, Serial No. 71,366

14 Claims. (Cl. 229—23)

This invention relates to compound cardboard box bodies, with particular reference to box bodies susceptible to further processing to form complete boxes of the cigar box type.

5 In United States Patents Nos. 1,839,779 and 1,970,582 we disclosed the formation of cardboard boxes particularly desirable for containers of cigars, although of course of wider implication than that comparatively restricted field.

10 In the earlier developments noted we disclosed the formation of a compound cardboard box body comprised of an outer shell of relatively thin cardboard and an inner tray of relatively thicker cardboard nested within the shell-forming walls of substantially the thickness of wood-

15 en cigar box walls so as to conduct toward a simulation of wooden cigar boxes. The box bodies thus formed were susceptible to any box purposes desired, but in the preferred instance

20 according to the latter of the above patents were subjected to trimming operations to cause the box bodies to have higher ends than sides, and with substantially squared upper edges, in any desired manner. It is preferred to trim the boxes by subjecting the bodies to the trimming secured by the device and according to the method disclosed in our Patent No. 1,970,581.

25 The box bodies as developed heretofore have been eminently pleasing, and upon every count 30 have been more satisfactory than the wooden boxes which they have replaced. The boxes are stronger, more resistant to moisture, and cheaper than wooden cigar boxes. Owing, however, to the cost of the thicker cardboard of the tray, 35 and to the relatively high labor cost of the assembly, there are numerous situations in which the present cardboard box body and box assembly could be even more economically produced to advantage if such cheapening could be secured 40 without sacrifice of the outstanding advantageous characteristics of the assembly.

45 It is among the objects of this invention; to provide a compound cardboard box body of simplicity and economy; to improve generally the construction of cardboard boxes; to provide a box body of great strength in which each corner has the same strength substantially as every other; to provide a compound box body comprised of a plurality of wall laminations having corners so ar- 50 ranged that no direct line of weakness extends through any corner so as to preclude rupture from a small strain; to provide a plurality of similar and relatively thin laminations in such manner as to avoid the use of thick cardboard in 55 a compound box body, without sacrificing any

of the desirable attributes normally flowing from the thick lamination; to provide a box body of lowered material cost; to provide a box body of lowered labor cost; to provide a box body utilizing components of the size and nature in part at least of scrap; and there are many other objects and advantages as will become more apparent as the description proceeds.

5 In carrying out the invention in a preferred form, a thin shell comprised of a bottom and four flaps stayed in box formation has disposed within it a plurality of partial necks in relatively overlapping relation, with a bottom and side wall covering semi-tray adherent within the necks and shell.

10 In the accompanying drawings:

Fig. 1 represents an exploded perspective of the components of the preferred form of compound box.

15 Fig. 2 represents a plan of the assembly of the preferred form,

Fig. 3 represents an enlarged fragmentary horizontal section through the compound box body of Fig. 2,

20 Fig. 4 represents a fragmentary transverse vertical section through the preferred form of device shown in Figs. 1 and 2, taken on line 4—4 of Fig. 2,

25 Fig. 5 represents a fragmentary longitudinal vertical section through the compound box body shown in Figs. 1 and 2 taken on line 5—5 of Fig. 2,

30 Fig. 6 represents a perspective of a semi-tray or innermost member of a modified form of box assembly,

35 Fig. 7 represents a plan of a box body according to the disclosure of Fig. 2, as modified by the use of the tray of Fig. 6,

40 Fig. 8 represents a perspective of a tray structure such as can be used with the compound structure of Fig. 2,

45 Fig. 9 represents a plan of a box body according to the easel of Fig. 2, as modified by the use of the tray of Fig. 8, whereby thicker ends than walls are provided,

50 Fig. 10 represents a perspective of an additional modified reinforcing member comprising a complete neck,

55 Fig. 11 represents a plan of a box body utilizing the full neck of Fig. 10 with the partial necks of Fig. 1 to secure a reinforced strengthened body of multiple laminations,

Fig. 12 represents a perspective of a further modified reinforcing element comprising a half neck,

Fig. 13 represents a plan of a compound box body built up with four of the half necks of Fig. 12 with a semi-tray member, and

Fig. 14 represents a fragmentary transverse vertical section through a box with a reinforced bottom wall.

In Fig. 2, there is disclosed a plan of a compound box body which is a preferred embodiment of the invention, and which is composed of individual component parts shown best, perhaps, in the exploded perspective of Fig. 1, to which reference may now be taken. The preferred foundation of the box is the shell 10, usually and preferably comprised of a bottom 11, end wall flaps 12 and 13 and side wall flaps 14 and 15. Each flap joins the bottom along treated lines 16, which usually are scored, or otherwise thinned, to facilitate bending of the flaps into wall portions. Adjacent flaps are disposed preferably in a somewhat mutually abutting relation and secured in place by the adherent stays 17. The stays may be reinforced as desired or a plurality may be provided at each corner in overlapping arrangement (not shown) and each is so arranged as to anchor adjacent flaps in a strong corner extending substantially the full depth of the shell. It will be apparent that as each bent flap of the shell is substantially an independent wall relative to its adjacent or contiguous neighbor in a corner, there is an interruption of the continuity of the wall texture and, in effect, a line of relative weakness 18 (as shown in Fig. 3) extends perpendicularly of the bottom for the depth of the box shell. The corners, however, are quite strong as the line noted is only relatively weakened.

It will also be apparent that each scored, or otherwise treated, line 16, comprises a line of relative weakness as compared to the unbent and unscored material of the adjacent bottom 11 and the respective panels or flaps hinged thereto. It is to be understood that as lines of weakness, the term is purely relative, as actually all of the joints or corners are quite strong.

The shell, as just described, is of rather thin material, and preferably, although clearly not essentially, of a single ply or lamination. To increase the thickness of the wall it is preferred that a three-quarter neck 20 be provided, comprising an end panel 21, a side wall 22, and an end panel 23, respectively separated by vertical lines of relative weakness 24. The end panels 21 and 23 of neck 20, are preferably of just the proper length so that when suitably adhesively coated and inserted within shell 10, they will just abut the interior of the shaped shell, and specifically, for illustrative purposes, to abut the wall 15 of the shell, when the neck has its middle extent 22 adhesively secured to the opposite side wall 14. Obviously, again purely illustratively, this will bring end wall 23 of the neck 20 against end flap or wall 13 of the shell. At this stage the compound box body comprises three double ply walls and one single ply wall.

A secondary three-quarter neck is provided, comprised of a middle extent 25 and end flaps 26 and 27 respectively connected by creases or lines of relative weakness 28, and which neck is externally adhesively coated and is introduced into the box body with the middle portion 25 against side wall 15, to form with shell flap 15 a double ply wall section, as will be clear. The end flaps of the secondary neck are then adhesively secured to the inner surfaces of the respective end flaps 21 and 23 of the primary three-

quarter neck, and terminate in abutment with the middle panel 22 of the said primary neck. In certain cases it is preferred that the secondary neck be of such finish on the inner exposed surface as to contribute, with other surfaces to be described, to the final inside finish of the completed box. Thus, illustratively purely, the secondary neck may have its inner surfaces of a calendered whitened surface, such as would comport with the desired finish of a cigar box, for instance. As thus far described, it will be clear that one inner side wall and both of the three ply end walls will have the desired finish, while the bottom and one side wall will be of the texture of the material of the shell and of the primary neck, respectively. The box body as thus described may be used for box purposes, or may have additional reinforcing elements, as later recited, associated with it. The partial necks just described, and to be described, may be, and are preferably, of the same weight cardboard as the shell, or they may be heavier or lighter than said shell.

A three-part semi-tray 30, comprising a body or bottom panel 31, and side walls 32 and 33, respectively joined to the bottom panel 31 with scored or weakened lines of bend 32, and the inner surfaces of which are preferably finished in the same manner as the secondary neck, is provided in adhesive engagement with the bottom 11, and with the inner portions of the respective middle panels 22 and 25 of the two necks.

The assembly as thus described is one which requires a minimum of labor, requires no special machinery for the assembly, although machine assembly under certain conditions is contemplated, and uses small units of material, such as might almost be characterized as scrap, and with light weight material furnishes a compound box body each wall of which is of at least three plies or laminations, and which when suitably dried can be trimmed off to establish neat upper edges, as for instance by a machine as shown by our Patent No. 1,970,581, or otherwise. The assembly just described affords a box body, the interior of which is of finished and attractive appearance, while the box is of appreciable strength. It is a desirable feature that each reinforcing element may be glued, or otherwise treated, then collapsed upon itself so as to be easily introduced, and then expanded into anchored engagement by manual manipulations, to avoid the difficulties of nesting one shaped and stayed or secured box form within another.

A word about the strength of the box may be noted at this juncture. The strength of the box is evident, if in existence, by the strength of the corners. The advantages of the instant construction can perhaps be better appreciated when it is observed that a piece of cardboard which is bent to shape, even after scoring, is usually stronger than two independent pieces of cardboard, however, joined at a corner. The flaw in necked boxes of the past, in considerable degree has lain in the fact that although three joints are quite strong indeed, the fourth, where the neck ends abut, is of such weakness that the boxes which do give way in service, break at this corner. In other illustrations of box bodies, a line of weakness is thought to exist at the corners, through linear alignment of the relatively weak points. Thus if three scored pieces of cardboard are bent and the corners nested or superimposed upon each other, the scoring or bend line of each will be in the same common line, and a

tearing or shearing strain incident upon the composite corner will possibly tend to rupture the whole by tearing each practically simultaneously. In the contemplation of this invention this alignment linearly of the weaknesses of the parts is obviated. Illustratively two scored joints are separated by an abutting neck end, so as to stagger the weakness line. It is believed that a factor in the strength of the box lies in this provision.

10 Referring to Fig. 3, it will be observed that the scored corner 24 of the primary neck formed by the intersection of side wall 22 with end flap 23 is strengthened by the extension of secondary end flap 27 over against neck side wall 22, with 15 which latter flap side wall 33 of the semi-tray abuts so that stresses must either pass directly through the solid overlapping parts just mentioned, or around their ends, with a consequent interruption in their continuity and consequent 20 resistance to rupture in response to such strains. The same characteristic misalignment holds true for each of the bottom joints as well, as shown in Figs. 4 and 5, so that the box of this invention is of great strength in all directions.

25 It will be obvious to those skilled in the art, that many modifications may be made in this invention without departing from its spirit, and certain of these will now be described.

As shown in Fig. 6, the semi-tray 34 of suitable thickness, usually the same as that of the necks, is provided with a bottom 35, and end flaps 36 and 37, with which a box body according to the disclosure of Figs. 1 and 2, built up with two three-quarter necks as described in 35 connection with those figures, is operatively associated so that a desired thickening of the end walls, while retaining the thinness of the side walls is secured. In the illustrative disclosure utilizing the tray of Fig. 6, as shown in Fig. 7, 40 the side walls are of but two plies.

In Figs. 8 and 9 there is illustrated the use of a complete but usually unstayed tray, comprising a bottom 38, end wall flaps 40 and 41 and side wall flaps 42 and 43. This enables the composite box 45 body already described (except for the tray) to have such additional reinforcements as to have the end walls of four plies while the side walls are of three plies. The ability to collapse the tray for purposes of insertion is an important advantage over a stayed and stiffened tray.

In Figs. 10 and 11, there is illustrated a neck having four walls, illustratively two end walls, respectively 44 and 45 and side walls 46 and 47, which is designed for operative association with 55 the quasi-necks and the shell already described. In this case, to avoid the corner weakness alluded to, the full neck has a line of jointure 49, either in a side, off from the center, so as to present no difficulties to nailing the box lids to the boxes 60 after filling, or in the end where the joint would be concealed by a subsequently applied wrap. In the preferred case the full neck of Fig. 10 is first associated with the shell and then the three-quarter necks already described may be inserted 65 as shown in Fig. 11, or the three-quarter shells may be substituted by the unstayed tray of Fig. 8 or any other desired inner member.

Figs. 12 and 13 represent a composite box body formed with the shell of Fig. 1, and the 70 semi-tray of the same, but with half necks, preferably four in number, and comprising each an end portion 48 and a side portion 50. With each glued in place in the shell in contact with one surface of adjacent half necks, a box body 75 of utility is formed. This may be used as com-

pleted, or may be further complemented by a suitable inner reinforcement.

It will be evident from the foregoing, that the walls may be thin or thick either in accordance with the numbers of plies or with the thickness of desired plies, or both, and that box walls may be built up to be as thick as desired. It will be recognized that in addition to the higher cost, thicker cardboard when scored and bent provides a deeper and more obvious groove at the corners than thinner board. When box bodies are formed according to this invention and trimmed by the machine set forth in the patent noted, the size of the groove of the inner member at a corner is of moment, despite the subsequent covering by a wrap, and, other things being equal, the inner member should be of such size or weight material as to minimize the groove line of weakening at the corner. This is an additional object obtained by the use of relatively thin material in the necks of the box.

The desirable attributes of staggering of the line of stress by staggering corners as described is carried out according to the invention in the bottom walls as well. Referring to Fig. 14, a 25 box is shown as set forth for instance in the structure of Figs. 1 to 5 inclusive, except for the provision of a bottom reinforcing wall 51 comprising a plane sheet or sheets of cardboard, which may be of light or heavy material and 30 thin or thick according to demands. Preferably, as a step in saving of labor, the sheet 51 is simply dropped into the shell without any adhesive upon either surface, although its adhesion to the bottom 11 is also contemplated. By insertion in 35 the shell, in wiping contact with the respective end and side walls thereof, it is held firmly in place by the inserted necks as shown, which rest upon its upper surface and provide with the insert a staggered stress line such as to strengthen 40 the assembly. The box may be completed by the insertion of the internally pasted or glued semi-tray 38, the bottom 31 of which is adherent to the upper surface of inserted sheet 51.

We claim:

1. A composite box body comprising a supporting structure, a pair of complementary necks each operatively associated with the supporting structure and with each other and continuous over three walls, and having overlapping relation on two walls.

2. A composite box body comprising a shell having a bottom, side and end walls, a reinforcement mechanically secured to two end walls and a side wall, a secondary reinforcement mechanically secured to the opposite side wall and the end engaging portions of the first reinforcements.

3. A composite box body comprising a shell having a bottom, side and end walls, a reinforcement mechanically secured to two end walls and a side wall, a secondary reinforcement mechanically secured to the opposite side wall and the end engaging portions of the first reinforcements, and means operatively associated with the assembly to increase the thickness of said side walls.

4. A composite box body comprising a shell having a bottom, side and end walls with adjacent side and end walls joined to form continuous side walls meeting in corners perpendicular to the bottom, a plurality of walls forming reinforcements operatively associated with the shell and each having a bent corner between legs of a length to substantially completely cover adjacent shell walls and so arranged that every shell corner is reinforced by a bent but continuous layer of wall

forming reinforcing material mechanically secured to the shell walls adjacent to such corners.

5. A box body comprising a shell having a body and four flaps bent into box form, means securing the corners of the bent shell, a four-sided neck having four corners and a termination spaced from the corners, a plurality of necks of less than four walls and corners each, the necks all operatively associated with each other and with said shell to form a box having reinforced multi-ply walls.

6. A composite box body comprising a shell having a bottom, side and end walls, a reinforcement mechanically secured to two end walls and a side wall, a secondary reinforcement mechanically secured to the opposite side wall and the end engaging portions of the first reinforcements, a tray comprising a bottom and side walls mechanically secured to the respective side wall engaging reinforcements.

7. In box bodies, means comprising a reinforced corner, said corner including divergent walls meeting in a corner with less strength than either wall and having a line of weakness at their apex substantially bisecting the corner, a reinforcement in engagement with and parallel to one wall and having an edge abutting the other wall and disposed across the line substantially bisecting the corner, and a secondary means having a line of weakness adjacent to said abutment with a line of weakness passing across said reinforcement, all of said walls forming said reinforced corner being adhesively secured together throughout their contacting surface.

8. A box body comprising a shell having walls and a bottom, a partial neck continuous over two ends and a side of the shell, a secondary partial neck continuous over the other side and over said first-mentioned neck portions over the shell ends, said secondary neck having a finished surface on said end reinforcements, a reinforcement for the bottom and sides having a finished surface, means securing the respective parts together so that the internal exposed surface will be comprised of the finished surfaces of the ends of the secondary neck and of the last-mentioned reinforcement.

9. A composite box body comprising a shell having a bottom, side and end walls, a reinforcement mechanically secured to two end walls and a side wall, a secondary reinforcement mechanically secured to the opposite side wall and the end engaging portions of the first reinforcements, and means operatively associated with the assembly to increase the thickness of a wall.

10. A composite box body comprising a shell having a bottom, side and end walls, a reinforcement mechanically secured to two end walls and a side wall, a secondary reinforcement mechanically secured to the opposite side wall and the end engaging portions of the first reinforcements, and means operatively associated with the assembly to increase the thickness of the end walls.

11. A composite box body comprising a shell having a bottom, side and end walls, a reinforcement mechanically secured to two end walls and a side wall, a secondary reinforcement mechanically secured to the opposite side wall and the end engaging portions of the first reinforcements, and means operatively associated with the assembly to increase the thickness of all of said walls.

12. A composite box body comprising a shell having a bottom, side and end walls, a reinforcement mechanically secured to two end walls and a side wall, a secondary reinforcement mechanically secured to the opposite side wall and the end engaging portions of the first reinforcements, and supplemental reinforcing means operatively associated with the assembly to increase the thickness of a wall, and secondary supplemental reinforcing means operatively associated with the assembly increasing the thickness of the bottom.

13. A composite box body comprising a shell having a bottom, side and end walls, a reinforcement mechanically secured to two end walls and a side wall, a secondary reinforcement mechanically secured to the opposite side wall and the end engaging portions of the first reinforcements and means reinforcing the bottom of the assembly.

14. A composite box body comprising a shell having a bottom, side and end walls with adjacent side and end walls joined to form continuous side walls meeting in corners perpendicular to the bottom, a plurality of bent one-piece reinforcements each having a single bend arranged one at each corner of the shell, each reinforcement being of a length and width to correspond to one end and side wall of the shell and arranged in overlapping relationship with adjacent reinforcements, and the reinforcements being adhesively secured to each other and to the shell walls to reinforce the corners and walls of said shell.
